UNITED STATES PATENT OFFICE.

BURT F. UPHAM, OF BOSTON, MASSACHUSETTS.

PRINTING-PRESS.

No. 909,260.

Specification of Letters Patent.

Patented Jan. 12, 1909.

Application filed August 23, 1908. Serial No. 450,689.

To all whom it may concern:

Be it known that I, BURT F. UPHAM, a citizen of the United States, and a resident of the city of Boston, in the county of Suffolk and Commonwealth of Massachusetts, have invented certain new and useful Improvements in Printing-Presses, of which the following is a full, clear, and exact description.

This invention pertains to two-revolution bed-and-cylinder presses, and it has for its objects the effecting of means whereby such presses can at will be adapted for printing in two colors, and also be converted in a moment into a high-speed two-cylinder press, 15 with the bed inoperative.

In all two-revolution cylinder presses, the cylinder is automatically raised during the return stroke of the bed, and in adapting the same for two-color work, I take advantage of 20 this fact by so arranging a small printing cylinder that the impression cylinder will recede therefrom by the same motion that causes the last-named cylinder to leave the plane of the bed.

25 To adapt the press for high-speed two-cylinder work, I provide means for disconnecting the bed from the operating mechanism of the press in such a manner that the bed will remain dead out of contact with the impression cylinder, while all the remainder of the machinery is running as usual.

Referring to the drawings forming part of this specification, Figure 1 is a side elevation of the press in diagram, showing the parts in 35 printing engagement. Fig. 2 is a similar elevation but with the impression cylinder elevated for the return stroke of the bed. Fig. 3 is a side elevation of the press, partly in section, showing some of its operative mechanism, and with the same adapted for high-speed two cylinder work. Fig. 4 is a detail sectional view of the bed reciprocating mechanism, showing my means for disconnecting the same from the remainder of the 40 machinery. Fig. 5 is a detail sectional view of one of the bearing boxes of the printing cylinder, showing the adjusting device therefor.

I have illustrated my improvements as applied to a press of a well-known Cottrell 50 type, but they are equally applicable to any form of two revolution lifting cylinder flat bed press. As shown in Fig. 3, the impression cylinder 1 acts in conjunction with the reciprocating bed 2, and is elevated out of 55 engagement with the latter during the return stroke thereof. The means for such eleva-

tion consist of the vertical rods 3 attached at their upper ends to the bearing boxes 4 of said cylinder's shaft, the springs 5, toggle 6, connecting rod 7 and cam 8 mounted on the 60 shaft 9.

The cylindrical printing surface 10 is rotatably supported a slight distance above possible contact with the bed 2, as shown in Fig. 1, but in printing engagement with the impression cylinder 1 when the latter is in engagement with the bed 2. The printing cylinder 10 being made considerably smaller in diameter than the impression cylinder, preferably of one half the size, the above-described 70 location of the printing cylinder will bring its line of contact with the impression cylinder substantially below the level of the latter's axis, and partially beneath the overhanging portion of the impression cylinder's periphery. Consequently, when the impression cylinder rises to avoid contact with the bed during the latter's return stroke, it will also draw away from the printing cylinder, and hence cause the latter to do no printing during substantially the same time that the bed 80 is not printing. This part of the operation of the press is illustrated by Fig. 2. It is of course understood that the said cylinders must be given equal superficial velocities, 85 and that the paper to be printed comes between the surfaces said to be in contact.

I prefer to mount each end of the shaft 11 of the printing cylinder in a box 12 horizontally slidable toward and from the impression cylinder in ways 13, as shown in Fig. 3. To accurately adjust these bearing boxes 12, I tap a bolt 14 into each thereof, passing such bolt through an internally and externally threaded sleeve 15 located in a suitably threaded opening 16 in said ways. Each sleeve is provided with a suitably shaped end 17 for enabling it to be turned by a wrench or other tool, and, inasmuch as its internal and external screw threads are 100 of different pitch, the turning of the sleeve upon its bolt will cause the latter and hence the bearing box to move toward or away from the impression cylinder, depending upon the direction of such turning. I prefer this arrangement of adjusting screw, for the reason that it is quite inconvenient to locate a set screw at the side of the ways 13 toward the impression cylinder, when it is attempted to use set screws for the purpose. 105

In the type of Cottrell press illustrated, it is customary to reciprocate the bed by

means of a rack 20 fixed thereto, and a toothed wheel 21 having its shaft 22 connected by means of a universal coupling to the shaft 23 on which is keyed, the gear 5 wheel 24 receiving power from the other actuating mechanism of the press, in which mechanism the gear 25 is the immediate element. In such a reciprocating means the toothed wheel 21 traverses first the upper 10 side and then the under side of the rack 20, as is well known.

In order to permit the impression cylinder and printing cylinder to operate without the conjunction of the bed, I wish to disconnect 15 this bed-reciprocating mechanism from the remainder of the machinery, so that the latter and said cylinders can work as usual, while the bed remains motionless at one side, as shown in Fig. 3. To do this, I prefer to 20 form the gear 24 in two concentric parts, 26, 27, each having a flange 28 overlapping the other, as shown in Fig. 4. One or more screws 29 are tapped through these flanges, so that, when bolted together, the power re- 25 ceived from the gear 25 by the toothed section 27 is transmitted to the inner section 26 and hence to the shaft and bed. By wholly or partially withdrawing such screw or screws, the toothed section 27 rotates freely 30 upon the inner section, and so fails to communicate motion to the bed, although all the other machinery is operating as usual. The bed being thus thrown out of commission, the machinery can be speeded up to any 35 proper limit, and the impression cylinder and printing cylinder coöperate as a high speed double cylinder press. In this manner, by attaching the small printing cylinder 10 to an ordinary type of two revolution bed-and- 40 cylinder press I am enabled to convert the same into a two color press, and hence capable of doing the work of two of the presses unequipped therewith, and at any moment can convert the press into a high-speed 45 printing machine of the two-cylinder type.

What I claim as my invention and for which I desire Letters Patent is as follows, to wit:—

1. The combination with a printing press 50 having a reciprocating bed and a lifting two revolution impression cylinder coacting therewith, of a printing cylinder given equal superficial velocity with the first-named cylinder and positioned to be in contact with the 55 latter when the same is in engagement with

the printing surface on the bed; said printing cylinder being substantially smaller than the impression cylinder and located close to said bed in order to engage the impression cylinder along a line far enough below the 60 level of the latter's center to cause said cylinders to be disengaged when the impression cylinder is elevated out of contact with said printing surface on the bed.

2. The combination with a printing press 65 having a reciprocating bed and a lifting two-revolution impression cylinder coacting therewith, of a printing cylinder given equal superficial velocity with the first-named cylinder and positioned to be in contact with the 70 latter when the same is in engagement with the printing surface on the bed; said impression cylinder being disengaged from the printing cylinder when the former is elevated out of contact with the printing surfaces on 75 said bed, and said bed being capable of being readily disconnected from the actuating mechanism of the press for permitting the two cylinders to act independently thereof.

3. The combination with a printing press 80 having a reciprocating bed and a lifting two-revolution impression cylinder coacting therewith, of a printing cylinder given equal superficial velocity with the first-named cylinder and positioned to be in contact with the 85 latter when the same is in engagement with the printing surface on the bed; said impression cylinder being disengaged from the printing cylinder when the former is elevated out of contact with the printing surface on 90 said bed, and said bed being capable of being readily disconnected from the actuating mechanism of the press for permitting the two cylinders to act independently thereof, the disconnecting means embracing a 95 spur gear meshing with the actuating mechanism of the press and connected with the bed-reciprocating means, and said gear consisting of two concentric sections having overlapping flanges rotatable relative to each 100 other and removable means for rendering said sections rigid with respect to each other.

In testimony that I claim the foregoing invention, I have hereunto set my hand this 27 day of August, 1908.

BURT F. UPHAM.
